UNITED STATES PATENT OFFICE.

GEORGE TAGGART, OF NICHOLS JUNCTION, MISSOURI.

BOX-MACHINE.

SPECIFICATION forming part of Letters Patent No. 643,279, dated February 13, 1900.

Application filed August 19, 1898. Serial No. 689,061. (No model.)

To all whom it may concern:

Be it known that I, GEORGE TAGGART, a citizen of the United States, residing at Nichols Junction, in the county of Greene and State 5 of Missouri, have invented certain new and useful Improvements in Box Forming and Making Machines; and I do hereby declare the following to be a full, clear, and exact description of the invention, such as will enable 10 others skilled in the art to which it appertains to make and use the same.

My invention relates to improvements in machines for making berry-boxes, the object of which is to quickly form, fold, and nail the 15 boxes. This object I attain by means of the device illustrated in the accompanying drawings, forming a part of this specification, in which—

Figure 1 is a perspective view of the machine, showing the device open. Fig. 2 is a perspective view from the opposite side, showing the device closed. Fig. 3 is a detail view of the device for folding shown open. Fig. 4 is a detailed view of the same closed. Fig. 25 5 is a vertical longitudinal section of the nail- 20 ing device. Fig. 6 is a longitudinal vertical section of the box which holds the berry-box bottoms. Fig. 7 is a longitudinal vertical section of the box which holds the sides of the 25 berry-boxes to be worked up. Fig. 8 is a longitudinal vertical section of the male portion of the former, showing the ejector. Fig. 9 is a perspective detail showing the male portion of the staple-former. Fig. 10 is a detail in 30 perspective of the female portion of the staple-former. Fig. 11 is a plan view showing the devices for feeding the wires into the machine to form the staples. Fig. 12 is an enlarged vertical section on line $x-x$ of Fig. 11, 35 showing in detail the feeding mechanism for feeding the wire into the machine for forming staples. Fig. 13 is an enlarged detail showing the ratchet for operating the feeding device. Fig. 14 is a detail vertical cross-section on line $y-y$, Fig. 5, showing the staple forming and driving device and showing the hammer. Fig. 15 is a similar view of this device, 40 showing the staple driven. Fig. 16 is another vertical section the same as Fig. 14, broken 45 away to show the projection R^5 . Fig. 17 is a top view of the staple-former, showing the springs $z-z^2$. Fig. 18 is a detailed view showing the

spring-pawl N^3 . Fig. 19 shows a modification of the device for making staples by means of a hand-lever and takes the place of the foot-piece S^5 , either to be used, with a preference for the hand-lever A^8 . Fig. 20 is a detail showing a modification of the ice-tongs device for connecting and disconnecting the treadle-rod D^2 . Fig. 21 is a vertical section of the 60 stapler, showing the levers R^3 lifted by the projections $P^2 P^3$. Fig. 22 is a detail showing the levers and catch for removing the side pieces. Fig. 23 is a detail perspective view of the completed berry-box. 65

Similar letters of reference represent corresponding parts in the several figures.

The framework A for supporting the device in an upright position may be made any desired size and shape for this purpose, having suitable supporting-rods A^2 . 70

B are upright supports to which is attached the lower or female portion of the die in which the berry-box is formed. This lower or female portion of the former C consists of an opening the size and shape of the box to be formed. 75

D is a male portion of the former and is attached to a sliding plate D^{18} , which works up and down in grooves B^2 of the uprights B . 80 The sliding former or male die D is provided with a rod D^2 for operating the same. This is accomplished by means of a foot-piece D^4 for drawing it down and a recoil-spring D^5 . Said rod D^2 is provided with a connecting 85 and disconnecting device, as shown in Figs. 4 and 20, the latter being a modification that may be used. In the former the clamps or ice-tongs $D^8 D^9$ are hinged to the upper part of the rod D^2 , the lower part D^6 being provided with an arrow-head D^7 , having beveled upper sides D^8 , and notches D^9 on the under side of the head. The uprights B are provided with projecting pieces D^{10} for catching the levers D^{11} of the clasps $D^8 D^9$ for throwing the claws D^{12} out of connection with the lower part of the rod D^6 . To keep said rod in position, it is provided with a sheath D^{13} , in which it slides up and down. In Fig. 20 the clasps $D^8 D^9$ are formed to operate by 90 coming in contact with the upper end of the sheath. In this case the projections D^{10} are dispensed with. The object of these clamps on the rod D^2 is to permit the operation of 95 100

the sliding folders E E² by the same treadle or foot-piece D⁴, for as the male former or die is seated in the female portion of the die the clamps D³ open and permit the treadle D⁴ to go on down, and by means of the rods F F², secured through the cross-piece F¹⁸, said cross-piece being attached to the foot-piece D⁴, and said rods extending thence upward are attached by means of chains F³ F⁴ to the sliding pieces E E². Said chains F³ F⁴ pass over rollers F⁵ F⁶, Fig. 3, so as to draw said slides forward as the foot-piece D⁴ moves on down. The lengths of the rods F F² are so adjusted that one of the slides will move forward in advance of the other for folding down one side of the berry-box in advance of the other. Said rods F F² are provided with springs F⁷ F⁸ below the cross-piece F³. Said springs are to permit the foot-piece D⁴ to move on down to operate the hammer for driving the staples, while holding the folders in position. The said folders leave a space between them to permit the staples to be driven through the folded sides of the berry-box. The slides E and E² are provided with recoiling-springs G G² for throwing the slides back after the box is nailed and the foot-piece D⁴ released.

The boxes are made of two pieces—a rectangular bottom piece I and a side piece H, having slots or eyes into which the corners of the rectangular bottom are inserted as the sides are wrapped around the bottom piece. The bottoms I and the side blanks H are held in two boxes or magazines, which are connected on the same frame J³, to be reciprocated horizontally from their normal position in Fig. 5 toward the dies C and D and back again. At each reciprocation a bottom is left caught by brads D¹⁴ on the male die D, and a side blank is left caught by catches K on the the folders E E² of the female die.

J is a box for holding the side pieces out of which the berry-boxes are to be formed. (See Figs. 5 and 7.) It has slots in the bottom J⁶, in which operates the brad K² on the front end of levers K. Said levers are secured to the slide pieces E and E² for drawing out one berry-box side piece at a time from the bottom of box J. For this purpose said box J has an opening J⁴ or slot the width to admit one berry-box side piece H to slide through at a time. Said box J is also provided with a weight or follower J² for holding the berry-box side pieces H firmly against the bottom 55 of box J, so that when the front side of box J strikes the projection K³ on the back end of lever K it raises the brad K² into the bottom piece of the berry-box side pieces and draws it out as the box J moves back.

M is a box for holding the bottom pieces I of the berry-boxes. (See Figs. 5 and 6.) Said box M is provided with suitable end pieces having springs M² M³ to firmly hold the bottoms I in position. The male die D is provided with brads D¹⁴ to enter the front one of the said bottom pieces I as they are moved forward, and as the box M moves back it

leaves one of the bottoms I attached to the front side of the male die D. Said box M is provided with a follower L, which operates as follows: The follower L is provided with cogs or teeth L² L³ on its upper and lower sides and with a stationary ratchet L⁴, having a spring L⁵ for operating on the follower L to prevent its flying backward. On its upper side it has a ratchet L⁶ for driving the follower forward, said ratchet being operated by means of a lever L¹², to which one end is secured. The other end of the lever has an arm L¹¹ to strike the stationary portion of the former C when the box M is moved forward for moving the follower L one notch forward, and a spring L⁷ is provided for throwing the pawl back one notch on the follower, and a yoke L¹⁵ is provided to prevent its going more than one notch at a time.

The boxes J and M are attached to a sliding rod or rack J³, which is provided with teeth or cogs J⁴ on its under side to be operated by a cog-wheel N, which is provided with suitable bearings in a support B⁵, secured to the upright B. Said cog-wheels N are operated by means of a lever N², by the operation of which the boxes J and M are moved back and forth. Lever N² also strikes the projection O⁴ of the ejector O² when the box is completed. This is accomplished by the projecting ends O⁵, which drive the completed berry-box off the male die D, and by means of the spring O³ the ejector is drawn back to position.

N³ is a spring-pawl, Fig. 18, for holding the male die D up while the staples are cut and formed. For this purpose one end of the spring-pawl N³ is attached to the axis of the cog-wheels N, the other end coming in contact with a projection N⁴ on the back side of plate D¹⁸, to which the male die D is attached.

The device for cutting and forming staples R consists of a feeding mechanism X on each side for feeding wires X¹⁶ X¹⁷ (see Figs. 11 to 17) into the cutting-machine. The feeding is accomplished by means of wheels X⁴, having a grooved edge X¹² and a tongue-edged wheel X³. Said tongue edge is milled or notched at X¹³ on its outer edge for firmly holding the wire to be fed into the machine. The bearings of one of the wheels, preferably X³, are provided with a spring X⁵ for firmly pressing the same against the wire. Said wheel is also provided with notches X¹⁸ on its upper surface, in which fits a ratchet or pawl X⁷ for driving the same. Said pawl is provided with a suitable spring X¹³ for holding the same back and a slot X⁸ for permitting it to slide back one notch in the wheel X³ at a time. It also has a projecting end X¹⁰ for striking one of the uprights P⁴ as they are carried forward by the motion of box M, to which said uprights P⁴ are attached. The wire on the opposite side is fed in a similar way. In said staple-forming device R is a frame having beveled openings W² for receiving the wires X¹⁶ X¹⁷, the inner edge of

said opening being sharp for cutting the said wires. In said frame R is placed a sliding sleeve V, Figs. 5 and 10, having racks or cogs V³ on each end for being operated up and down by means of cog-wheels R² R², Fig. 5, having levers R³ R³, which are weighted at the outer ends and provided with cogs for moving said sleeve V up and down as said lever is operated.

10 P is a male portion of the staple-former, having three projections P² P³ P⁶, with openings or depressions P⁷ P⁸ between. The openings are to receive the ends of the sleeve V. The projections P² P³ operate the levers R³ of the cog-wheels R² to force the sleeve V down over the projection P⁶, which enters it as the sleeve goes down and cuts off the staple from the wires X¹⁶ X¹⁷ and forms the staple out of the piece cut off, which is forced up into the sleeve V by the projection P⁶ against the lower side of the hammer S². The spring of the piece of wire thus formed into a staple holds itself in position in the sleeve V, while the former P⁶ is removed and goes back with box 20 M, to which it is attached. When the staple is formed, the staple-forming device is moved up, which releases the male portion of the die P, which enables it to move back to its normal position.

25 The hammer S² is driven down when the sleeve V and its frame W rest upon the top side of the berry-box H on the upper side of the male die D. (See Fig. 15.) The upper surface of the male die D is provided with groove D¹⁹, Fig. 15, for turning the points of the staple Y outward as it is being driven in opposite directions and upward to clinch the same for holding the sides H firmly together. The hammers S² are provided with a weighted 30 head S, to which they are attached. The weighted hammer S and the staple-former are provided with rods S³ R⁴, respectively. Rod S³ is provided with a suitable foot-piece S⁵ at the lower end for forcing the same downward in driving the staples and a suitable recoil-spring Q R for raising the same. The other rod R⁴ is secured so as to be operated by the foot-piece D⁴ as it passes downward and is also provided with a suitable recoil-

40 spring. Springs Z Z² have clasps Z⁴, which catch the levers R³ when raised by the projections P² P³ and hold them in position, and when the hammers S² are driven downward through slot S⁴ they are bevel-edged, as shown, 45 so as to spread the springs Z Z² as the hammers descend, thus releasing the levers R³, which, being weighted, drop back of their own weight and throw the sleeve V back up above the openings in a position to form another 50 staple. Said sleeve is steadied in position by a projection R⁵, Fig. 16, which enters the sleeve as it goes up.

The device is thus operated: Strips of wood or the like ordinarily used for berry-boxes, 55 having slots for receiving the corners of the bottoms, are laid in box J, Fig. 5, and weighted down by J². Said box has the slot J⁴ at

the lower front edge the thickness of one strip and slots J⁶, Fig. 7, in its bottom. Said box J is attached to the sliding rack-bar J³ 70 for the purpose specified and operated, as stated above, by lever N³. Strips of wood as ordinarily used for the bottoms of berry-boxes are placed in box M, Figs. 5 and 6, and operated as above specified. After one of 75 the bottoms I has been attached to the male former D and a side strip H is held on the female former by the brads on levers K, as stated above, the treadle D⁴ is depressed, which moves the male die from position in 80 Fig. 3 down to Fig. 4, entering the female die by the male die D and forming the ends of the box. In this downward movement the arms D³ strike the cams or projections D¹⁰ and strip the arrow-head (or it may be accomplished as shown in Fig. 20) just as the male die D is seated. Continued downward motion of D⁴ causes the cross-piece F¹⁸ to draw rods F F² and by the chains F³ F⁴ draws the sliding folders E E² forward one ahead of 85 the other and folds the sides of the berry-box down over the male die D. Continued downward pressure of D⁴ compresses springs F⁷ F⁸ and draws down the rods R⁴, which are attached to treadle D⁴, but may be attached to treadle S⁵, and this forms the staple, 90 as above specified, and brings the staple against the box H. The pressure downward, then, of foot-piece S⁵ drives the staple. Releasing the foot-piece S⁵ and treadle D⁴, the 100 springs above described bring the device back to the normal position. Throwing the lever N³ then farther forward the completed box is ejected.

In modification shown in Fig. 19 the springs 105 F⁷ and F⁸, as shown in Fig. 3, are removed from the under side of the foot-piece and placed on top of the same and are provided with sheaths and ice-tongs for being operated the same as rod D².

Having thus described my invention, what I claim as new, and desire to secure by Letters Patent, is—

1. In a box-making machine the combination of the female die C; male die D; rod with 115 treadle D⁴, clamps D³, D³, and recoil-springs D⁵, with folding slide-pieces E, E², for folding down the sides of the box all substantially as shown and described for the purpose specified.

2. In combination with a stationary die C, of the sliding die D, a rod D² clamps D³, D³, sliding folders E, E², operated by means of rods connected with the foot-piece on rod D², and recoil-springs all substantially as shown and described. 120

3. In a box-forming device a stationary die C, and a sliding die, D, having a disconnecting-rod D², said disconnecting-rod, D², having clamps D³ D³ for catching a head D⁷, on rod D⁶ opened by means of cams D¹⁰ and folding-slides E, E², connected with the foot-piece D⁴, on rod D⁶ said slides having recoil-springs G, G², all constructed and combined for the purpose specified. 125 130

4. In a box M, for holding bottom pieces of boxes to be formed the combination of end springs M², M³ with a follower L, having a lever and ratchets for operating the said follower and brads on the male die D, for taking out one bottom at a time as the reciprocating movable box M, is moved forward and back all substantially as shown and described. 35
5. In combination with a box-forming device consisting of two reciprocating boxes J, M, holding the side pieces H, and bottoms I, a stationary die, C, and a movable die, D, with a staple-forming device consisting of a frame R, having sleeve V, and former, P, and levers R², and hammers, S, all substantially as shown and described. 40
6. In combination with a staple-forming device consisting of a frame R, having a sleeve V, lever R², and a reciprocating male former, P, of a wire-feeding mechanism consisting of milled, tongue-and-grooved wheels X³ X⁴, one having spring-bearings X⁵, the other propelled by a spring-pawl X⁷ all substantially as shown and described. 45
7. In a box-making machine the combination of a staple-forming mechanism consisting of wheels X³, X⁴, provided with a pawl X⁷, for feeding the wire, and a frame R, provided with a sleeve V, and levers R², and a reciprocating male former P; with a staple-driving device consisting of a hammer S, with spring-rod S³, all substantially as shown and described. 50
8. The combination in a box-making machine of a box-former consisting of a stationary female die, C, and a movable male die, D, and reciprocating boxes J, M, containing the sides H, bottoms I, with a staple forming and driving mechanism above it substantially as shown and described. 55
9. A box-forming mechanism operated by means of a lever N², for reciprocating the boxes J and M, combined with a separable treadle-rod D², for operating the male dies, D, and rods F, F², for operating the folding-slides E, E², and a rod R⁴, for operating the staple-former and a rod S³, for operating the hammer for driving the staples, all substantially as shown and described. 40
10. In combination with a wire-feeding mechanism as described; of a staple-forming device consisting of a frame W, having a sliding sleeve, V, operated by cog-wheels as specified and a male former P, all constructed and operated substantially as set forth. 50
